CHILD'S TOY JUMPING HASSOCK

Lydia Jedwabnik, New York, N.Y., assignor to A & L Novelty Co., Inc., Brooklyn, N.Y., a corporation of New York

Filed Jan. 7, 1965, Ser. No. 83,321

Term of patent 7 years

(Cl. D34—15)

FIG. 1 is a top and end perspective view of a child's toy jumping hassock taken from one direction, showing my new design;

FIG. 2 is a top and end perspective view taken from the other direction thereof;

FIG. 3 is an end elevational view thereof;

FIG. 4 is a top plan view thereof; and

FIG. 5 is a side elevational view thereof.

The doll is an integral part of the hassock and permanently attached thereto as shown.

I claim:

The ornamental design for a child's toy jumping hassock, as shown, and described.
